UNITED STATES PATENT OFFICE.

HORACE H. BURDETT, OF HOPEDALE, MASSACHUSETTS, ASSIGNOR TO DRAPER CORPORATION, OF HOPEDALE, MASSACHUSETTS, A CORPORATION OF MAINE.

INTERMITTENTLY-OPERABLE TAKE-UP MECHANISM FOR LOOMS.

Application filed December 11, 1925. Serial No. 74,744.

This invention relates to improvements in looms and the object thereof is to provide mechanism for weaving an open mesh fabric, such as tobacco cloth or netting, with 5 re-enforcing stripes formed by closely massing the filling at predetermined intervals and preferably during predetermined periods.

A further object of the invention is to provide a novel mechanism for producing a transverse re-enforcing stripe in the web of fabric by intermittently interrupting the positive movement of the take-up roll by mechanism operable conjointly by the lay 15 and the means for actuating the take-up roll at predetermined intervals acting temporarily to release the take-up roll from operative relation to its actuating means.

A further object of the invention is to provide means for releasing the take-up roll from its actuating means operable by the movement of the lay, with means operable by said actuating means to restore the rotational movement of the take-up roll after a 25 predetermined period.

A further object of the invention is to provide various adjustments by means of which the formation of the transverse re-enforcing stripes may be accurately controlled.

Other objects and features of the invention will more fully appear from the following description and the accompanying drawings and will be particularly pointed out in the claims.

The present invention is adapted to be applied to usual forms of looms and is illustrated herein as applied to the take-up mechanism of the usual Northrop type of loom illustrated in Patent No. 982,390 Rhoades 40 granted January 24, 1911. Only so much of the take-up mechanism is illustrated in the drawings as is necessary to disclose the present invention and its application to the loom of the type above described.

In the drawings:

Fig. 1 is a front elevation of the take-up mechanism, partially broken away and partially in section;

Fig. 2 is a view, partially in elevation and 50 partially in section, on line 2—2 Fig. 1, viewed from the right toward the left; and,

Fig. 3 is a view showing the general type of weave produced by the take-up mechanism forming the subject matter of the invention.

Fig. 4 is a detail view illustrating the relative position of the members of the clutch actuating mechanism in a position intermediate of those shown in full and dotted lines respectively in Fig. 2.

The take-up mechanism illustrated herein comprises a usual take-up roll 1 having a gear 2 adapted to mesh with a pinion 3 on the shaft of the cloth roll 4 to impart rotation to the latter until the roll of cloth 5 is of sufficient diameter to be readily driven by frictional engagement with the take-up or sand roll. The shaft 6 of the take-up roll is mounted in suitable bearings in a bracket 7 extending from the frame of the loom and 65 has rotatably mounted upon its end portion a take-up gear 8 which meshes with and is driven by an actuating gear 9 which is a part of a train of gears which may be driven from the cam shaft of the loom in the manner disclosed in the prior patent to Rhoades, or in any other suitable manner.

Clutch mechanism is provided for releasably connecting the hub 10 of the take-up gear to the shaft 6 of the take-up roll. 70 In the preferred construction illustrated herein in the hub of the take-up gear is provided with a serrated face which is engaged by a complementary serrated face upon a clutch member 11 which is slidably mounted upon 75 the shaft 6 of the take-up roll and is secured against rotation thereupon by a key and slot connection 12. The clutch member 11 is provided with an annular groove 13 which is engaged by trunnions 14 upon a clutch 80 shifter 15 which is in the form of a yoke the arms of which are pivotally mounted upon brackets or extensions 16 projecting from the bracket 7 in which the take-up roll shaft is journalled. The clutch shifter is 85 provided with a downwardly extending relatively wide flat arm 17 presenting at its lower end portion a beveled face 18 merging into a relatively wide flat portion 19. A helical spring 20, surrounding the take-up shaft 100 6 and engaging at one end the bracket 7 and at the other end the clutch member 15,

acts normally to maintain the clutch members in engagement and thereby to cause continuous rotation of the take-up roll.

The present invention comprises means operable through the actuating means at predetermined intervals to release the clutch members from engagement and thereby to permit stoppage of the rotation of the take-up roll.

10 In order to prevent retrograde movement of the take-up roll when thus released a ratchet 21, which is fixedly secured to the gear 2 of the take-up roll by suitable pins 22 (see Fig. 2), or in any other suitable manner, is engaged by a pawl 23 pivotally secured upon a bracket upon the loom frame and which operates to prevent reverse rotation of the roll.

The preferred means for intermittently releasing the clutch illustrated herein comprises a clutch actuating device which is rotatable with the actuating gear 9, but is adapted to be moved relatively to the gear by suitable mechanism, preferably operable by

25 the lay, for the purpose of releasing the clutch and to have a lost motion until again engaged and released by suitable mechanism carried by the gear, thus providing a sufficient period of lost motion to permit a number of weft threads to be laid compactly while the take-up roll is stationary, after which the take-up roll will again be actuated continuously to provide the proper spacing for the weft threads.

35 In the preferred construction illustrated herein the clutch-releasing mechanism comprises a clutch releasing arm or lever 24 which is pivotally mounted upon the shaft 25 of the actuating gear 9. This arm is normally engaged and rotated with the gear by a pin or stud 26 which engages the rear face of the arm and is adjustably secured in a slot 27 in the web of the gear. Desirably a spring 28 tends normally to hold the arm in engagement with the stud 26. The arm 24 is provided with an extension 29 upon the opposite side of its pivotal shaft 25 which desirably is provided with a bifurcated end portion upon which a dog 30 is pivotally mounted upon a stud 31. The dog illustrated preferably is of curved form and is provided with a V-shaped re-entrant end face 32. The dog is normally held in position by an adjustable stud 33 seated in a transverse web in the extension 29 and abutting against a shoulder 34 at the pivot end of the dog.

40 The V-shaped end of the dog 30 is adapted to be positioned during the rotation of the gear 9 in direct alignment with a dagger 35 which is slidably mounted in suitable journals in a bracket 36 which is secured to the loom side 37. The dagger 35 desirably has a squared end portion which is slidably mounted in a complementary guideway in

one of the members 38 of the bracket 36. The opposite end portion 39 of the dagger desirably is of cylindrical form and is slidably mounted in a suitable bearing in the member 40 of the bracket 36. A pin 41, 75 which extends through the cylindrical portion of the dagger, is normally held against the member 40 of the bracket by a helical spring 42 which surrounds the rectangular portion of the dagger and abuts at its opposite end against the member 38 of the bracket 36. A screw threaded rod 43 is adjustably seated in the cylindrical end portion of the dagger and is provided with a head 44 adapted to be engaged by the lay sword 45 upon its beat-up. The screw threaded rod 43 is provided with a check nut 46 by means of which it may be held in adjusted position. The bracket 36, as illustrated herein, is provided with an extension 47 having vertical slots 48 to receive bolts 49 which clamp said extension to the side frame 37, thus providing means for adjusting the bracket vertically.

45 A dog-arresting member 50 is mounted 90 upon the horizontal web 51 of the bracket 36 and is secured thereto by a bolt 52 which passes through a slot 53 in said dog-arresting member, thus providing a connection by means of which the dog arresting member 95 can be adjusted longitudinally of the bracket, this dog-arresting member preferably being positioned approximately in the horizontal plane of the axis of the shaft 25 of the actuating gear 9.

50 The function of the dog-arresting member 50 is to hold the dog out of operative relation to the end of the dagger 35 during the relatively slow rotation of the actuating gear 9 until such time that the dog when released 105 may drop quickly into alignment with the dagger, thereby providing means for actuating the clutch releasing arm at a definite predetermined time.

55 In the operation of the mechanism illustrated herein the actuating gear 9 rotates the take-up gear 8 positively and uniformly. Normally the clutch members are held in engagement by the helical spring 12 and the take-up roll is therefore positively and uniformly rotated during the normal weaving operation. As the actuating gear rotates, the engagement between the stud 26 and the clutch releasing arm 24 causes the clutch releasing arm to be carried along progressively by the rotation of the gear until it reaches nearly the position illustrated in dotted lines in Fig. 2. At this time the projecting notched end portion 32 of the dog will engage the dog-arresting member 50 which will hold that end of the dog temporarily from further movement as the arm approaches the clutch shifting member 19. When the arm has rotated sufficiently so that upon release the dog will drop into the 110

horizontal position illustrated in Fig. 2, the dog drops from its arresting member 50 and falls by gravity into the horizontal position illustrated in dotted lines in Fig. 2 at which time the notch 32 in its end is in alinement with the end of the dagger 35. Upon the next beat-up of the lay the lay sword engages the head 44 of the dagger and forces the dagger forwardly (at the left of the position illustrated in Fig. 2) thus engaging the end of the dog and forcing it forwardly, thus rotating the arm 24 upon its pivot so that the beveled face 24* of the clutch actuating arm rides up upon the beveled face 18 of the clutch shifting member and causing the clutch shifting member to slide the movable clutch member 11 upon the shaft 7 until the clutch is released. The clutch actuating member then remains in this position retaining the clutch members out of engagement until the rear face of the arm 24 is again engaged by the stud 26, whereupon further rotation of the gear will again move the arm 24 with the gear until the arm slides off of the flat face 19 of the clutch shifting member, thereby permitting the spring 12 to restore engagement of the clutch members so that the take-up roll will again be positively driven through the intermeshing gears 9 and 8. In order to limit the field of movement of the clutch shifting arm 24 a stop, preferably in the form of a stud 54, is adjustably secured in a slot 55 in the actuating gear 9. This stop acts to prevent an over-throw of the clutch releasing arm which might otherwise be caused by the force of the blow given to the dog 30 by the dagger 35 when the latter is actuated by the lay.

It will thus be seen that the take-up roll is positively driven during the normal weaving operation, but is arrested temporarily during the period of lost motion which intervenes between the clutch releasing movement of the arm 24 when actuated by the lay and the time in which the clutch releasing arm is again engaged by the stud 26 upon the actuating gear 9 and forced out of engagement with the clutch shifting arm 17 by further continuous rotation of the actuating gear 9.

It will be understood that the embodiment of the invention disclosed herein is of an illustrative character and is not restrictive and that various changes in form, construction and arrangement of parts may be made within the spirit and scope of the following claims.

Having thus described the invention, what is claimed as new, and desired to be secured by Letters Patent, is:

1. Intermittently actuated take-up mechanism for looms having a reciprocating lay, operable to produce transverse re-enforcing stripes in the web of fabric, comprising a take-up roll, continuously rotating means

for actuating said take-up roll and means operable conjointly by the lay and said actuating means, at predetermined intervals, to release said take-up roll temporarily from operative relation to said actuating means. 70

2. Intermittently actuated take-up mechanism for looms having a reciprocating lay, operable to produce transverse re-enforcing stripes in the web of fabric, comprising a take-up roll, continuously rotating means for actuating said take-up roll, means operable conjointly by the lay and said actuating means, at predetermined intervals, to release said take-up roll temporarily from operative relation to said actuating means and means for varying the length of the period during which said take-up roll is released. 80

3. Intermittently actuated take-up mechanism for looms having a reciprocating lay, operable to produce transverse re-enforcing stripes in the web of fabric, comprising a take-up roll, means including a continuously rotating gear for actuating said take-up roll and means rotatable co-axially with said gear operable conjointly by the lay and by said gear to release said take-up roll temporarily from operative relation to said actuating gear during a predetermined period in each cycle of rotation of said actuating gear. 90

4. Intermittently actuated take-up mechanism for looms, operable to produce transverse re-enforcing stripes in the web of fabric, comprising a take-up roll, continuously rotating means for actuating said take-up roll, a clutch intermediate of said actuating means and said take-up roll, a clutch releasing device rotatable with said actuating means and capable of a predetermined lost motion relatively thereto and means for actuating said releasing device to release said clutch and retain the members thereof in inoperative position during said period of lost motion. 100

5. Intermittently actuated take-up mechanism for looms, operable to produce transverse re-enforcing stripes in the web of fabric, comprising a take-up roll, continuously rotating means for actuating said take-up roll, a clutch intermediate of said actuating means and said take-up roll, a clutch releasing device carried by said actuating means capable of a predetermined lost motion relatively thereto and means operable by the movement of the lay for actuating said clutch releasing device to release said clutch and to maintain the members thereof released during the period of lost motion. 110

6. Intermittently actuated take-up mechanism for looms, operable to produce transverse re-enforcing stripes in the web of fabric, comprising a take-up roll, continuously rotating means for actuating said take-up roll, means operable by the lay at predetermined intervals to release said take-up roll 120

from operative relation to said actuating means and means operable by said actuating means to restore operative relation between said take-up roll and said actuating means.

7. Intermittently actuated take-up mechanism for looms, operable to produce transverse re-enforcing stripes in the web of fabric comprising a take-up roll, a take-up gear, a clutch intermediate of said gear and said roll, an actuating gear engaging said take-up gear, a clutch-releasing arm rotatable coaxially with said actuating gear, a member on said actuating gear normally engaging said arm and rotating the same in unison therewith, means operable by the movement of the lay to advance said arm rotatably a predetermined distance relatively to the movement of said actuating gear and to cause said arm to release said clutch and retain the same in inoperative position until said arm is again engaged by said member.

8. Intermittently actuated take-up mechanism for looms, operable to produce transverse re-enforcing stripes in the web of fabric, comprising a take-up roll, a take-up gear, a clutch intermediate of said gear and said roll, an actuating gear engaging said take-up gear, a clutch-releasing arm rotatable coaxially with said actuating gear, a member on said actuating gear normally engaging said arm and rotating the same in unison therewith, means operable by the movement of the lay to advance said arm rotatably a predetermined distance relatively to the movement of said actuating gear and to cause said arm to release said clutch and retain the same in inoperative position until said arm is again engaged by said member and means for adjusting the field of movement of said arm.

9. Intermittently actuated take-up mechanism for looms, operable to produce transverse re-enforcing stripes in the web of fabric, comprising a take-up roll, a take-up gear, a clutch intermediate of said gear and said roll, an actuating gear engaging said take-up gear, a clutch-releasing arm rotatable coaxially with said actuating gear, a member on said actuating gear normally engaging said arm and rotating the same in unison therewith, a dog pivotally mounted upon said arm, a dagger positioned to engage said dog when in a predetermined position and operable by the movement of the lay to advance said arm relatively to the movement of said actuating means and to cause said arm to release said clutch and retain the same in inoperative position until said arm is again engaged by said member.

10. Intermittently actuated take-up mechanism for looms, operable to produce transverse re-enforcing stripes in the web of fabric, comprising a take-up roll, a take-up gear, a clutch intermediate of said gear and said roll, an actuating gear en-

gaging said take-up gear, a clutch-releasing arm rotatable coaxially with said actuating gear, a member adjustably mounted on said actuating gear normally engaging said arm and rotating the same in unison therewith, a dog pivotally mounted upon said arm, a dagger positioned to engage said dog when in a predetermined position and operable by the movement of the lay to advance said arm relatively to the movement of said actuating means and to cause said arm to release said clutch and retain the same in inoperative position until said arm is again engaged by said member and a co-operating adjustable stop member mounted on said gear operable to limit the advancing movement of said arm.

11. Intermittently actuated take-up mechanism for looms, operable to produce transverse re-enforcing stripes in the web of fabric, comprising a take-up roll, a take-up gear rotatably mounted upon the shaft of said take-up roll, a spring actuated clutch normally connecting said take-up gear to said roll, a normally continuously rotated actuating gear meshing with said take-up gear, a clutch-releasing arm, a stud on said actuating gear normally engaging said arm and causing the same to rotate in unison with said gear, a gravity operated dog pivotally mounted upon said arm, means for temporarily arresting the dropping movement of said dog above horizontal position during a portion of the revolution of said gear, a dagger positioned to engage said dog when the latter drops to horizontal position during further rotation of the gear and operable by the movement of the lay to engage and actuate said dog and thereby cause said arm to disengage the clutch and render it inoperative until said arm is engaged by said stud.

12. Intermittently actuated take-up mechanism for looms, operable to produce transverse re-enforcing stripes in the web of fabric, comprising a take-up roll, a take-up gear rotatably mounted upon the shaft of said take-up roll, a spring actuated clutch normally connecting said take-up gear to said roll, a normally continuously rotated actuating gear meshing with said take-up gear, a clutch-releasing arm, a stud on said actuating gear normally engaging said arm and causing the same to rotate in unison with said gear, a gravity operated dog pivotally mounted upon said arm, means for temporarily arresting the dropping movement of said dog above horizontal position during a portion of the revolution of said gear, a dagger positioned to engage said dog when the latter drops to horizontal position during further rotation of the gear and operable by the movement of the lay to engage and actuate said dog and thereby cause said arm to disengage the clutch and render it

inoperative until said arm is engaged by said stud and means for limiting the movement of said dog about its pivot, whereby accurate alinement with said dagger may be established.

13. Intermittently actuated take-up mechanism for looms, operable to produce transverse re-enforcing stripes in the web of fabric, comprising a take-up roll, a take-up gear rotatably mounted upon the shaft of said take-up roll, a spring actuated clutch normally connecting said take-up gear to said roll, a normally continuously rotated actuating gear meshing with said take-up gear, a clutch-releasing arm, a stud on said actuating gear normally engaging said arm and causing the same to rotate in unison with said gear, a gravity operated dog pivotally mounted upon said arm, means for temporarily arresting the dropping movement of said dog above horizontal position during a portion of the revolution of said gear, a dagger positioned to engage said dog when the latter drops to horizontal position during further rotation of the gear and operable by the movement of the lay to engage and actuate said dog and thereby cause said arm to disengage the clutch and render it inoperative until said arm is engaged by said stud and means for vertically adjusting the position of said dagger.

14. Intermittently actuated take-up mechanism for looms, operable to produce transverse re-enforcing stripes in the web of fabric, comprising a take-up roll, a take-up gear rotatably mounted upon the shaft of said take-up roll, a spring actuated clutch normally connecting said take-up gear to said roll, a normally continuously rotated actuating gear meshing with said take-up gear, a clutch-releasing arm, a stud on said actuating gear normally engaging said arm and causing the same to rotate in unison with said gear, a gravity operated dog pivotally mounted upon said arm, means for temporarily arresting the dropping movement of said dog above horizontal position during a portion of the revolution of said gear, a dagger positioned to engage said dog when the latter drops to horizontal position during further rotation of the gear and operable by the movement of the lay to engage and actuate said dog and thereby cause said arm to disengage the clutch and render it inoperative until said arm is engaged by said stud, means for limiting the movement of said dog about its pivot, whereby accurate alinement with said dagger may be established and a stop stud adjustably mounted in said gear to limit the advancing movement of said arms.

15. Intermittently actuated take-up mechanism for looms, operable to produce transverse re-enforcing stripes in the web of fabric, comprising a take-up roll, a take-up gear rotatably mounted upon the shaft of said take-up roll, a spring actuated clutch normally connecting said take-up gear to said roll, a normally continuously rotated actuating gear meshing with said take-up gear, a clutch-releasing arm, a stud on said actuating gear normally engaging said arm and causing the same to rotate in unison with

said gear, a gravity operated dog pivotally mounted upon said arm, means for temporarily arresting the dropping movement of said dog above horizontal position during a portion of the revolution of said gear, a dagger positioned to engage said dog when the latter drops to horizontal position during further rotation of the gear and operable by the movement of the lay to engage and actuate said dog and thereby cause said arm to disengage the clutch and render it inoperative until said arm is engaged by said stud and means for vertically adjusting the position of said dagger.

16. Intermittently actuated take-up mechanism for looms, operable to produce transverse re-enforcing stripes in the web of fabric, comprising a take-up roll, a take-up gear rotatably mounted upon the shaft of said take-up roll, a spring actuated clutch normally connecting said take-up gear to said roll, a normally continuously rotated actuating gear meshing with said take-up gear, a clutch-releasing arm, a stud on said actuating gear normally engaging said arm and causing the same to rotate in unison with said gear, a gravity operated dog pivotally mounted upon said arm, means for temporarily arresting the dropping movement of said dog above horizontal position during a portion of the revolution of said gear, a dagger positioned to engage said dog when the latter drops to horizontal position during further rotation of the gear and operable by the movement of the lay to engage and actuate said dog and thereby cause said arm to disengage the clutch and render it inoperative until said arm is engaged by said stud and means for temporarily arresting the dropping movement of said dog above horizontal position during a portion of the revolution of said gear, a dagger positioned to engage said dog when the latter drops to horizontal position during further rotation of the gear and operable by the movement of the lay to engage and actuate said dog and thereby cause said arm to disengage the clutch and render it inoperative until said arm is engaged by said stud and means for adjusting said dog-arresting means, whereby said dog may be retained out of the path of the dagger until the arm is so positioned that the end of the dog will drop into alinement therewith.

In testimony whereof, I have signed my name to this specification.

HORACE H. BURDETT.
